UNITED STATES PATENT OFFICE.

BION B. FARNHAM, OF KENMORE, NEW YORK.

DRYING-MACHINE.

1,091,051.

Specification of Letters Patent. Patented Mar. 24, 1914.

Application filed March 25, 1913. Serial No. 756,812.

To all whom it may concern:

Be it known that I, BION B. FARNHAM, a citizen of the United States, residing at Kenmore, in the county of Erie and State of New York, have invented a new and useful Drying-Machine, of which the following is a specification.

This invention relates to improvements in veneer drying machines.

10 An object of the present invention is to provide a drying machine with a large number of drying rolls and with the drying rolls driven in pairs from a main driving shaft.

15 A further object is to provide means whereby the rolls are supplied with steam for the heating thereof and also means whereby the water of condensation will be removed as it forms.

20 With the foregoing and other objects in view which will appear as the description proceeds, the invention resides in the combination and arrangement of parts and in the details of construction hereinafter described and claimed, it being understood that 25 changes in the precise embodiment of the invention herein disclosed, can be made within the scope of what is claimed, without departing from the spirit of the invention.

25 In the drawings accompanying this specification and forming a part thereof, the preferable form of my invention has been illustrated, in which:

30 Figure 1 is a front view in elevation partially sectional in character and illustrating the drying rolls, the method of introducing steam therein and the removing of water therefrom. Fig. 2 is a top fragmental view of my improved drying machine. Fig. 3 is a side view in elevation showing the 35 driving side. Fig. 4 is a side view in elevation showing the steam supply side.

35 Referring to the drawings in which similar reference numerals designate corresponding parts throughout the several views, 1—1 represents the supporting legs to the upper extremities of which are secured the I-beams 2—2 there being two of the said I-beams extending longitudinally of the machine and forming the base or foundation structure 40 upon which the rollers and various driving mechanisms are mounted. The legs 1 at the front and rear of the machine are extended as at 3 and to the upper extremity of which is secured the beam 4. Extending 45 between the top flange 5 of the I-beam 2 and the uppermost beam 4 are the bearing

supporting members 6, each member being provided with a flange 7 at its upper and lower extremities, which flanges are rigidly secured to the said beam 4 and I-beam 2. The 50 bearing supporting members 6 are spaced a distance apart so as to support the bearings for the drying rollers, each pair of supporting members 6 rigidly supporting a lower roller and movably supporting an upper 55 roller thereabove.

The rolls 8 are cylindrical in outline and are arranged in pairs one above the other as illustrated in Fig. 4 of the drawings, there being a large number of the so arranged rollers which extend transversely of the machine. To one end of these hollow cylindrical rolls are secured the flanged trunnions 9, the flanges 10 thereof being bolted to suitable bosses 11 formed at the 60 ends of the rolls, or may be secured thereto by brazing or other means as per the upper roll of Fig. 1. The trunnions 9 are rotatably mounted in the bearing boxes 12. To the outer extremities of the trunnions 9 are 65 rigidly keyed the spur gear wheels 13—13. The trunnion 9 of the lower roll is rotatably mounted within its bearing box, which bearing box is rigidly secured between the bearing supporting members and the lower roll 70 8 is thereby held against lateral or vertical movement. The upper bearing box which supports the upper roll is mounted 75 slidably between the bearing supporting members 6 and is provided with an upwardly extending lug or boss 14 secured to which is the rod 15. The said rod 15 extends through a suitable aperture formed in the beam 4 and is held against lateral movement by the same. Extending between the 80 lower surface of the beam 4 and the upper surface of the bearing box is the spring member 16 which forces the upper roller 85 downward into contact with the lower roller and holds the same resiliently thereagainst. 90 In order to limit the relative movement of the two rollers the nuts 17 are secured to the upper extremity of the rod 15 and are adapted to contact with the beam 4 and to prevent excessive movement of the said rolls. 95 100 The spur gear wheels 13 which are rigidly secured to the extremities of the trunnions 9 are provided with elongated teeth so that the two rollers may shift to a slight extent without danger of bringing the two gear 105 wheels out of mesh. Extending longitudinally of the entire machine and rotatably

110

mounted in suitable bearings is the driving shaft 18, power being transmitted thereto by means of the gear wheels 19, 20 and 21, the gear wheel 19 being rigidly secured to the driving shaft 18 and the gear wheel 21 is driven by some suitable source of power. The intermediate wheel 20 is mounted upon a bell crank arm 22 which is pivotally secured to the end post 3 as at 23. The wheel 20 is journaled within a slot 24 formed in one arm of the bell crank lever 22 and the other arm thereof is adjustably secured within a slot 25. The purpose of the intermediate gear wheel 20 is to provide means whereby power may be transmitted from the gear wheel 21 to wheel 19 and also to provide means whereby the gear 19 may be shifted a slight distance with relation to the gear 21. As illustrated in Fig. 3 the shaft 18 is provided with worm gears 26 and these worm gears 26 contact with and actuate the lower spur gears 13 which latter gears in turn drive the spur gears thereabove. In this manner power is transmitted from the driving shaft 18 through the worm gears 26 to the lower spur gear of each pair of rollers and this gear in turn drives the one thereabove from which it will be apparent that there will be as many worm gears upon the driving shaft 18 as there are pairs of the drying rolls, and also that the power transmitted to the various rolls is not transmitted through all the other rolls but is derived directly from the actuating shaft 18.

From the foregoing it will be understood how the various pairs of drying rolls are actuated and the manner in which the power is supplied thereto. In order to supply the heating medium which will usually be steam to the interior of the cylindrical rolls 8 the hollow trunnions 27 are rigidly secured to the ends of the cylindrical rolls 8 and these trunnions are rotatably mounted upon the I beams 2 and between the upper beam 4 in a manner similar to that in which the trunnions 9 are mounted, the lower trunnion being rigidly secured in place by having its bearing box rigidly secured and the upper trunnion is mounted to slide with respect to the lower one by resiliently securing the bearing box to the upper beam 4. The outer extremity of the trunnions 27 are provided with the flanged packing joint 28 whereby the pipe 29 is passed through the aperture which extends through the said trunnions 27 and effects a tight joint therewith, the packing joint in question comprising the flange 30 with the outer flange member 31 detachably connected thereto, the same being clearly illustrated in Figs. 1 and 2 of the drawings. The pipe 29 which communicates with the interior of the upper roll is provided with the valve 32 for regulating the flow of steam to the said pipe and the said valve 32 communicates with a steam

supplying main 33. It is to be noted as shown in Fig. 4, that the steam is supplied to the lower rolls by means of the pipes 34 which extend between each of the said rolls and communicates with the leaden pipe 29 thereof. The lower rolls are supplied by means of the main 34 it being noted that the mains 33 and 34 communicate with a suitable supply. In order that the water of condensation may be removed from the various rolls approximately as fast as it condenses, the pipes 35 are positioned within the steam supplying pipe 29 and extend therethrough. The extremities of the pipes 35 are bent downward as at 36 and are spaced a short distance from the inner periphery of the rolls 8. The pipes 35 therefore, will act as a siphon whereby the water of condensation will be constantly removed from the cylindrical rolls 8 and therefore the entire rolls will be subject to the heating action of the steam.

The pipes 35 extend beyond the steam pipes and communicate with the main 37, it being noted that as the steam enters the cylindrical rolls 8 a pressure will be obtained therein which will force the water of condensation out through the pipes 35 into the main or a suitable vacuum may be maintained within said main which will insure that the water of condensation will flow from the cylindrical rolls 8 into the pipes 35. It is to be noted in this connection that the upper roller being provided with adjustable bearings requires that the piping which extends through the trunnions thereof be provided with means whereby the shifting of the said roller will not tend to distort the piping and with this object in view the pipe 29 may be lengthened so as to provide for sufficient resiliency thereof which will allow the upper roller to shift with relation to the lower roller, or a suitable sliding (not shown) joint may be installed within the piping or other equivalent means whereby the desired effect will be secured.

My improved drying machine is particularly adapted to dry veneer and the adjustable manner in which the upper rolls are supported provides that any unevenness of the veneer will be suitably taken care of. The lower or carrying roller is rigidly supported in its stationary bearings and means have been provided for the introducing of steam therein and the draining of the water of condensation thereon, the result being that the lower roller will have the entire inner periphery thereof subject to the heating action of the steam. The upper or compressed roller is mounted directly above and contacts with the lower roller and is adapted to shift relative thereto. These rollers are also adapted to receive steam or other heating mediums therein and also means have been provided whereby these

rollers will always be maintained practically free of any water of condensation. The manner in which the various rolls are driven provides that a large number of the rolls 5 may be assembled in one machine which would otherwise be impractical if the power was transmitted from roll to roll by means of spur gearing.

Having thus fully described the invention

10 what I claim to be new and original with me is:—

1. In a drying machine, the combination of a pair of spaced base beams, a pair of spaced top beams mounted above the said 15 base beams and carried thereby, bearing supporting members arranged in pairs and rigidly secured to the top and base beams, bearings slidably disposed between the said bearing supporting members, resilient means 20 engaging said bearings and the top beams adapted to hold the same resiliently in place, hollow cylindrical carrying and compress rolls rotatably carried by said bearings and arranged in pairs, means for admitting 25 steam and exhausting the water of condensation to and from said cylindrical rolls, and means for positively driving each of said rolls.

2. In a drying machine, the combination 30 of a pair of base beams, bearing supporting members rigidly secured to said beams and extending upwardly therefrom, top beams carried by the upper extremities of said bearing supporting members, bearings slidably disposed within said bearing supporting 35 members, resilient means engaging the top bearing and the top beam to resiliently hold the former in place, hollow cylindrical carrying rolls extending transversely of the 40 base beams, and arranged in pairs, one end of said cylindrical rolls provided with flanged trunnions, said trunnions journaled within said bearings, gear wheels rigidly secured to the extremities of the trunnions, 45 a shaft extending parallel to the said base beams provided with worm gears secured thereto meshing with the gear wheels of the lower cylindrical rolls, the opposite ends of said hollow cylindrical carrying and 50 press rolls provided with flanged trunnions secured thereto, said trunnions provided with apertures extending axially therethrough and provided with packing joints

at the outer extremities thereof, steam inlet pipes extending through said trunnion apertures and effecting a steam-tight and rotatable joint therewith, steam controlling valves communicating with said steam inlet pipes of the upper rolls, steam mains communicating with said steam valves and said steam 60 inlet pipes, discharge pipes fitting within said steam inlet pipes and provided with the inner extremities thereof bent downward within the carrying rolls and terminating adjacent the lower inner surfaces thereof 65 adapted to conduct the water of condensation therefrom, discharge mains communicating with said discharge pipes, the said valves adapted to control the supply of steam to the upper cylindrical rolls. 70

3. In a drying machine, the combination of a pair of base beams, bearing supporting members rigidly secured to said beams and extending upwardly therefrom, top beams carried by the upper extremities of said 75 bearing supporting members, bearings slidably disposed within said bearing supporting members, resilient means engaging the top bearing and the top beam to resiliently hold the former in place, hollow cylindrical 80 carrying rolls extending transversely of the base beams, and arranged in pairs, one end of said cylindrical rolls provided with flanged trunnions, said trunnions journaled within said bearings, gear wheels rigidly 85 secured to the extremities of the trunnions, a shaft extending parallel to the said base beams provided with worm gears secured thereto meshing with the gear wheels of the lower cylindrical rolls, the opposite ends of 90 said hollow cylindrical carrying and compress rolls provided with flanged trunnions secured thereto, said trunnions provided with apertures extending axially therethrough and provided with packing joints 95 at the outer extremities thereof, means for admitting steam and exhausting the water of condensation to and from said cylindrical rolls.

In testimony that I claim the foregoing 100 as my own, I have hereto affixed my signature in the presence of two witnesses.

BION B. FARNHAM.
